Inventor:

Burton Scott,

By his Attorney, Leo P. Misch

UNITED STATES PATENT OFFICE.

BURTON SCOTT, OF NEW YORK, N. Y.

ELECTRICALLY-ACTUATED SOUND PRODUCER.

Application filed August 31, 1922. Serial No. 585,564.

To all whom it may concern:

Be it known that I, BURTON SCOTT, a citizen of the United States, and a resident of the borough of Manhattan, city, county, and State of New York, have invented certain new and useful Improvements in Electrically-Actuated Sound Producers, of which the following is a specification sufficient to enable those skilled in the art to which the invention appertains to utilize the same.

While applicable to electrically actuated sound producing and amplifying devices for various other purposes, my invention is designed primarily for use in conjunction with what are known generally as loud music or talking "receivers" of the magnetic or electro-magnetic type, my main object being to attain a simple and inexpensive operative device of this character in which accurate adjustment of the area of an open magnetic gap may be effected with facility, and extraneously, substantially in the manner and for the reasons hereinafter fully set forth.

In the accompanying drawings, I illustrate a practical embodiment of the essential features of my invention, although I do not limit myself to the identical form and construction of parts shown, since modifications in minor details, or equivalent mechanical expedients may be resorted to, without departing from the spirit and intent of my invention in this respect, and with like results.

With this understanding,

Fig. 1, is an exterior elevation of my electrically actuated sound producer;

Fig. 2, is a central vertical sectional elevation thereof, taken upon plane of line 2—2, Fig. 4;

Fig. 3, is a central vertical sectional elevation thereof, taken upon plane of lines 3—3, Figs. 1 and 2;

Fig. 4, is a transverse section taken upon plane of line 4—4, Fig. 2;

Fig. 5, is a perspective view of the elastic resilient conversion diaphragm;

Fig. 6, is a perspective view of the permanent magnet;

Fig. 7, is a perspective view of the vibratory armature and its supporting spring plate;

Fig. 8, is a perspective view of the two blocks upon and between which the armature spring plate is mounted;

Fig. 9, is a perspective view of the bearing

block attached to the free end of the permanent magnet;

Fig. 10, is a perspective view of the tie rod by which the armature and the converter diaphragm are positively connected so as to vibrate in unison;

Fig. 11, is a sectional elevation of the lower portion of my sound producer showing a modification in the means provided for the adjustment of magnetic gap between armature and coil core.

Fig. 12, is a detail view illustrating a modification of the means of gap adjustment shown in Fig. 1;

Fig. 13, is a sectional detail of a modification in the form of armature;

Fig. 14, is a sectional detail of a modification of the means of magnetic gap adjustment.

C, represents the main shell or casing, preferably although not necessarily, of cylindrical configuration with a bottom plate c, formed, in the construction illustrated in the first four figures of the drawings, with two openings, one, c', for the accommodation of the electric circuit wires connected with core-coil E, the other, c'', for the intrusion of the head s, of the adjusting screw S. The upper edge of the casing C, is rigidly attached to the cup plate C', by screws c³, c⁴, or equivalent means, said cup plate C', being male screw-threaded peripherally for engagement with the corresponding female screw thread on the annular clamping ring i, formed with the inturned flange i', which bears against the external edge k, of the cap plate K, between the inner circumferential edge of which, and the upturned edge c⁵, of the cup plate C', the sound conversion diaphragm D, is peripherally supported as shown in Figs. 2 and 3 of the drawings,—the edge of said diaphragm D, being provided with the usual binding gasket g, and the mounting and support of the diaphragm D, being also otherwise essentially the same as heretofore known in the art.

The under side of the cap plate K, is recessed as at k, to afford the necessary scope of vibration for the diaphragm D, in action; and said cap plate K, is also formed or provided with the throat duct k', with which the base of the horn H, (indicated by dotted lines in Figs. 1 and 2) is connected.

The upper arm m, of the U-shaped or

other bent form of permanent magnet M , is rigidly attached to the under side of the cup plate C' , as shown more particularly in Fig. 1, of the drawings,—the other arm m' , of said magnet being free, so that the permanent magnet M , is, practically, suspended on and from said cup plate C' .

Upon the free arm m' , of the permanent magnet M , is mounted the electro-magnetic core e , and its coil E , by any suitable means, as by rigidly supporting the core e , by and between flanged base plates m^2 , m^2 , affixed to the upper side of said free lower arm m' , of the magnet M , as indicated particularly in Figs. 2, 3, and 11, or by equivalent mechanical expedients.

The armature A , is supported upon mounting blocks a , a' , rigidly secured to the upper arm m , of the permanent magnet M , and to the cup plate C' , or otherwise supported in fixed medial relation to the permanent magnet M , and coil E so as to position the said armature A , in proper juxtaposition to the core e , of the said electric coil E . For this purpose the armature A , may be provided with an elastic resilient leaf spring a^x ; or in certain cases, the flat elastic resilient spring a^x , may itself be utilized to function as the armature A , as indicated in Fig. 13, as for instance where a loud sound is not desirable.

In either case the armature A , is rigidly connected with the sound-conversion diaphragm D , by a tie rod R , in such manner as to transmit the vibratory motion of said armature A , superinduced through the medium of the core e , by the excitation of the electric coil E , in a manner well known in the art, my present invention relating more particularly to the means for varying the single gap area between said core e , and the said armature A , as herein set forth.

The tie rod R , consists preferably of a relatively thin narrow flat strip r , as shown in detail in Fig. 10, its upper extremity being attached to a head r' , formed with a screw stud r^2 , for engagement with a nut r^3 —said screw stud r^2 , protruding through the central perforation d , in the diaphragm D , and the latter being clamped by the nut r^3 , against the head r' , as indicated in Figs. 2 and 3 of the drawings. The flat plane of the rod strip r , is positioned at right angles to the plane of flexure of the armature A , so as to allow the strip r , to bend easily, and thus neutralize as far as possible the side strain.

The lower extremity of the strip r , of the tie rod R , extends through a transverse slot a^2 , in the arm a^3 , of the armature A , and is clamped to said arm a^3 , by means of a set screw a^4 , which also affords a convenient means whereby the distance and tension between the armature A , and the diaphragm D , may be regulated and set with accuracy.

Both the upper arm m , of the permanent magnet M , and the cup plate C' , are, of course formed with openings for the accommodation of the tie rod R , as shown in Figs. 2 and 3. By this means of connecting the armature A , and diaphragm D , I obviate all looseness or play between said parts, and the rattle and disturbance incidental to the use of the link movements heretofore in vogue, and at the same time attain the requisite degree of copulative flexibility.

The U-shaped or bent form of permanent magnet M , has sufficient resilience to be utilized as a bow spring in controlling the magnetic gap area between the core e , and the armature A , its tendency being to hold them apart to the maximum degree of efficiency. Hence, to decrease this maximum area of gap, and regulate the same with accuracy, I provide means whereby the lower arm m' , of the permanent magnet M , may be forced toward the upper arm m , thereof, thereby raising the electro-magnet E , and its core e , as related to the normal position of the armature, which is prescribed by the mounting thereof on the said upper fixed arm m , of the permanent magnet M .

This adjustment of gap between core e , and armature A , may obviously be effected by various mechanical expedients, two of which are shown by way of exemplification in the drawings. Thus in Figs. 1, 2, 3, and 14 thereof, I illustrate the use of a non-magnetic adjusting screw S , for the purpose, whereas in the modification shown in Fig. 11, an eccentric S^x , is employed for the same purpose.

In the case of the non-magnetic screw S , shown in Figs. 2 and 3, its upper extremity is formed with a micrometer thread s , for engagement with a female screw thread formed for the purpose in the block a' , which supports the armature spring plate a^x , the lower extremity of said screw S , being provided with a manipulative head s' , having a shoulder s^2 , which bears either directly against the lower arm m' , of the magnet M , as shown in Fig. 12, or indirectly against said lower arm m' , through the medium of a washer s^3 , contacting with a bearing block m'' , attached to the under side of said lower arm m' , of the magnet M , as shown more particularly in Figs. 2 and 3 of the drawings.

In the simpler construction shown in Fig. 14, the inner end of the adjusting screw S , simply bears, either directly, or indirectly, against the lower arm m' , of the permanent magnet M .

Thus by turning the screw S , in either direction by means of its manipulative head s' , positioned extraneously of the casing C , the single magnetic gap between core e , and armature A , may be conveniently regulated with accuracy; or a like result may be at-

tained by turning the eccentric S^x , (Fig. 11) on its pivotal support by means of the extraneous handle s^x , which latter may be provided with a spring detent s^x , for engagement with a rack s^{x_2} , concentric as related to the pivotal support of the eccentric S^x .

In either case the same result may be attained, in that the distance between the lower arm m' , of the permanent magnet M , and the upper arm m , thereof may be varied to adjust the electro-magnet E , and its core e , in position as related to the normal position of the vibratory armature A , for the purpose herein set forth. Furthermore, this is accomplished extraneously in a simple manner, without opening up the casing or otherwise disturbing the operative parts contained therein, the device, in a unitary sense, remaining intact under all conditions and requirements of use.

The amplifying power scope of the sound producing diaphragm attained by the combination of permanent magnet and electro-magnetic core as related to the vibratory armature as herein set forth, is obvious to those conversant with the art to which my invention and device appertains, as well as the various practical uses to which the device may be applied.

I have thus far described the construction and function of the operative parts in utilizing the expansive force of the permanent magnet as fixing the maximum of magnetic gap between armature and electro-magnetic core, and the adjusting means as used to press the free arm of the permanent magnet toward the fixed arm thereof, for the purpose of contracting the gap area, although it is obvious that the reverse or alternative method may be resorted to with like result. That is to say, the minimum of gap between armature and core may be attained by the contractive tendency of the permanent magnet and its arms, and the adjusting means be used to retract the free arm m' , as related to the fixed arm m , in order to increase the area of said gap.

In either case the extent of adjustment may be restricted within safe bounds by means of a stop or stops.

What I claim as my invention and desire to secure by Letters Patent is,—

1. In an electrically actuated sound producer of the character designated, the combination of a permanent magnet formed with essentially parallel arms, one of which is fixed and the other relatively free, an electro-magnetic coil and core mounted on the free arm of said permanent magnet, an armature mounted in prescribed relation to the fixed arm of the permanent magnet and connected with a sound converting diaphragm, said diaphragm, and means for adjusting the free arm of said permanent magnet with relation to the fixed arm thereof, for

the purpose of regulating the magnetic gap between the electro-magnetic core and said armature, the connection between said diaphragm and said armature consisting of a relatively thin flat tie rod arranged with its flat plane substantially at right angles to the plane of flexure of the armature in the manner and for the purpose set forth.

2. In an electrically actuated sound producer of the character designated, the combination of a permanent magnet formed with essentially parallel arms, one of which is fixed and the other relatively free, an electro-magnetic coil and core mounted on the free arm of said permanent magnet, an armature mounted in prescribed relation to the fixed arm of the permanent magnet and connected with a sound converting diaphragm, said diaphragm, and means for adjusting the free arm of said permanent magnet with relation to the fixed arm thereof for the purpose of regulating the magnetic gap between the electro-magnetic core and said armature, comprising a set screw coupling the free arm of said permanent magnet with the fixed block on which the said armature is mounted, substantially in the manner and for the purpose set forth.

3. In an electrically actuated sound producer of the character designated, the combination of a permanent magnet formed with essentially parallel arms, one of which is fixed and the other relatively free, an electro-magnetic coil and core mounted on the free arm of said permanent magnet, an armature mounted in prescribed relation to the fixed arm of the permanent magnet and connected with a sound converting diaphragm, said diaphragm, and means for adjusting the free arm of said permanent magnet with relation to the fixed arm thereof for the purpose of regulating the magnetic gap between the electro-magnetic core and said armature, comprising a set screw coupling the free arm of said permanent magnet with the fixed block on which the said armature is mounted, and the connection between said diaphragm and said armature consisting of a relatively thin flat tie rod arranged with its flat plane substantially at right angles to the plane of flexure of the armature, as and for the purpose set forth.

4. In an electrically actuated sound producer of the character designated, the combination of a permanent magnet formed with essentially parallel arms, one of which is fixed and the other relatively free, an electro-magnetic coil and core mounted on the free arm of said permanent magnet, an armature flexibly mounted on the fixed arm of said permanent magnet and connected with a sound converting diaphragm, said diaphragm, and means for adjusting the free arm of said permanent magnet with

relation to the fixed arm thereof, for the purpose of regulating the magnetic gap between the electro-magnetic core and said armature, substantially in the manner and for the purpose set forth.

5. In an electrically actuated sound producer of the character designated, the combination of a permanent magnet formed with essentially parallel arms, one of which 10 is fixed and the other relatively free, an electro-magnetic coil and core mounted on the free arm of said permanent magnet, an armature flexibly mounted on the fixed arm 15 of said permanent magnet and connected with a sound converting diaphragm, said

diaphragm, and means for adjusting the free arm of said permanent magnet with relation to the fixed arm thereof for the purpose of regulating the magnetic gap between the electro-magnetic core and said 20 armature, said adjustive means comprising a set screw coupling the free arm of said permanent magnet with the fixed arm thereof, substantially in the manner and for the purpose set forth.

BURTON SCOTT.
